UNITED STATES PATENT OFFICE

JOHN P. WEIS, OF NYACK, NEW YORK, ASSIGNOR TO METROPOLITAN SEWING MACHINE CORPORATION, OF NYACK, NEW YORK, A CORPORATION OF DELAWARE

MACHINE AND METHOD FOR FORMING FRENCH-FELLED SEAMS

Application filed December 2, 1929. Serial No. 411,013.

This invention relates to sewing machines and particularly to an improved machine and method for making multiple seams in various articles, such as the legs of trousers, overalls, and the like, in one operation with a single handling of the work by the operator, and which machine is comparatively simple in construction and operation and by means of which the seams of the character described may be expeditiously and less expensively produced.

A further object of the invention is the provision of an improved machine and method for first stitching superposed parts or plies of an article with a row of stitches, subsequently automatically opening or separating unstitched portions of the plies and reversing or overturning a ply, and then stitching the severallapping plies with another row of stitches in parallelism with the first row of stitches, thereby to form what is known as a French-felled seam.

Another object of the invention is to so combine a plurality of sewing mechanisms in tandem relation with cooperating means therebetween to convey and guide the work from one to the other automatically, thereby to form a French-felled seam having a plurality of spaced lines or rows of stitches, whereby superposed plies of the article may be first stitched together with a row of stitches, one ply thereof overturned, and the triple plies again stitched with another row of stitches in parallelism with the first row to form the seam.

Another object of the invention is the provision of a machine and method in which superposed plies of fabrics are first stitched together with a durable elastic stitch, one of the plies reversed or overturned in a direction opposite to the bottom ply whereby it is folded over in position to receive a second line of durable elastic stitches, thereby to form a French-felled seam in a single operation instead of two separate and distinct operations, as heretofore.

Another object of the invention is the provision of an improved machine so organized in connection with overturning, guiding, and controlling means co-operating therewith

that a plurality of plies of material may be fed horizontally in a flatwise position to the left of the needle of one sewing mechanism and stitched with a row of stitches, a ply thereof then reversed or overturned, and the triple plies then stitched with a row of stitches located to the right of the first row of stitches and in parallelism therewith.

In the stitching of certain kinds of clothing and other articles to make a French-felled seam well known in the art, it has always required, first, the stitching by an operator on one sewing machine of two plies of material to form a seam along the marginal edges of the material to join them together, then the plies are subsequently separated and the seam margins folded over either to the right or left as the work is guided through a second sewing machine by a second operator. These two separate operations have heretofore been necessary to make a French-felled seam, regardless of what the article may be. The skill required in the second operation made it more expensive than the first operation, in addition to which has to be considered the cost of shifting the work from one operator to the other and the delay incident thereto. In my improved method the work is accomplished in a very simple manner with one operator in a single pass through the machine of the material, effecting a substantial saving in the cost of the operation as well as offering other obvious advantages.

The improvement is particularly useful for making the outside leg seams of overalls, trousers, and other clothing, and also the heel seams and the like in canvas and other shoes, and various other articles of manufacture.

In this improved machine for making French-felled seams, under certain operating conditions on some kinds of articles, the general arrangement and design of the guide and control members may be altered without departing from the scope of the invention. For instance, the flop-over control means, the shape of the cloth guiding member, the scalloped portion of the seam control, and the general arrangement of the parts may all be varied to suit different operations for producing the French-fell or similar seams,

either with single or multiple needle stitching mechanisms with plain or ornamental stitches that are well known in the art, without departing from the spirit of this invention. Therefore, in the present instance, while, for the purposes of description, the invention is described and illustrated particularly for use in the manufacture of overalls, shoes, and the like, this is not to be understood as a limitation, as it is obvious that the improvement may be used with equal facility on a great variety of articles requiring multiple stitching for the seams, and when such articles require two or more lines or rows of stitches showing on the outside, the second sewing mechanism can readily be provided with two or more needles to meet such requirements.

In the drawings accompanying and forming a part of this specification—

Fig. 1 is a front end view of this improved machine for making a French-felled seam in one operation by one handling of the work by a single operator;

Fig. 2 is a top plan view of the machine shown in Fig. 1;

Fig. 3 is a perspective of the driving mechanisms of this machine;

Fig. 4 is a detail view of the work edge guide, with the superimposed plies of work in position for stitching, and a part of the ply turnover means;

Fig. 5 is a top plan view of the presser foot with the folding guide attached thereeto;

Fig. 6 is a side view of Fig. 5;

Fig. 7 is a detail perspective, partly sectional, view of the seam edge guide and the ply turnover means;

Fig. 8 is a perspective view of the seam edge guide and needle of the first sewing mechanism and illustrates two superposed plies of material adjacent to the stitching position;

Fig. 9 illustrates the superposed plies of material after receiving the first row of stitches with the top ply partially reversed or turned over;

Fig. 10 illustrates the top ply further folded over, prior to receiving the second row of stitches; and

Fig. 11 illustrates the two plies of work with the completed French-felled seam after it has passed the second stitching mechanism.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

In constructing this machine I preferably use two of the well-known "Metropolitan" sewing machines, although any other make of machine could be used since the invention is not limited to any particular kind of sewing machine or stitching mechanism. In the present instance I use two single needle stitching mechanisms arranged in tandem relation and spaced apart to permit the reversal of a portion of the work as the material passes from one to the other. This spacing may be varied to suit the character of work and the kind or design of article to be stitched. It is important, however, to have the space between the two stitching mechanisms sufficient to permit a gradual folding-over or overturning of the top ply of material from a left to a right-hand position so as to feed freely to and through the second or rear stitching mechanism.

In the preferred form thereof, this improved machine is mounted on a table 1, preferably an individual table equipped with power driving means for operating the two sewing mechanisms 2 and 3, which rest on and are secured to the table. A description of one sewing mechanism will suffice for both, since they are alike except for some slight details which will be described in connection with the handling of the work. Each, therefore, is equipped with the usual stitching instrumentalities comprising a needle 4, presser foot 5, and feeding mechanism 6. Driving belts 7 and 8 are provided for operating the two sewing mechanisms; belt 7 operates sewing mechanism 2, while belt 8 operates sewing mechanism 3. An electric motor 9 is mounted on a shaft 9' with which a clutch 10 is connected for coupling and uncoupling a drive pulley 11 with the motor 9. This clutch is under the control of a foot treadle 12 connected by chain 13 to a clutch lever 14, whereby the machine may be started and stopped at will and the speed varied and controlled according to the skill of the operator. The top shafts of the sewing mechanisms are provided with hand wheels 15 for the usual purpose.

Attached to the cloth plate of the front sewing mechanism 2 is a work edge guide 16 (see Figs. 2 and 4) for controlling the edges 17 of the goods 18 to be stitched. The line or row of stitches 19 is usually placed about one-quarter of an inch from the edges of the material. In advance of the toe 20 of the presser foot of the first sewing mechanism 2 and at the left thereof and conveniently located is the forwardly-projecting end 21' of the work separating and overturning or flop-over means 21. This end 21' lies parallel with the top surface of the cloth plate of the sewing mechanism 2, having a space 22 (see Fig. 1) therebetween to provide clearance for the free passage of the bottom ply of the work or material to be stitched. This bottom ply is

fed across the cloth plate in a flat position, while the top ply is separated therefrom and feeds up over the inclined edge 23 forming a part of the overturning means 21. This vertical edge reaches its full height at about 24 and then slants downward, as at 25, terminating at the end 26 just in advance of the stitching instrumentalities of sewing mechanism 3. This overturning means is adjustably secured by clamp screws 27 passing through elongated slots in a forwardly-projecting plate 28 formed as a part of a face plate 29 for the head of sewing mechanism 3, this plate covering and protecting the needle driving mechanism thereof and is secured to the head by screws 30 tapped into the head of the top arm of the machine. By this organization the entire overturning means is properly supported and held in operative position relatively to the cloth plates and stitching instrumentalities of the two sewing mechanisms to accurately control the work. This overturning means is provided with a right-angle scalloped flange 31 (see Figs. 2, 4 and 7) which acts as a controlling means to prevent or limit any lateral shifting of the stitched seam as it passes from the sewing mechanism 2 to the sewing mechanism 3. The scallop form of the flange lessens the friction on the work as it is fed from one stitching position to another. This scalloped flange 31 is so spaced relatively to the throat 32 of a trough or U-shaped guide 33 so as to properly regulate the seam margin between the row of stitches 19 and the free edges 17 of the work, so that the proper width or margin 34 (see Figs. 9 and 10) is maintained uniformly throughout the length of the seam. This trough-shaped guide 33 comprises a bottom, laterally-extending portion 35 extending from one cloth plate to the other to support the work and an overhanging top portion 36 to hold the work against vertical movement and thereby keep it under control. The edge 33' forms a guide for the folded portion of the overturned ply. The front end of this trough-shaped guide is shaped, as at 37, adjacent the first stitching position to permit the feed of sewing mechanism 2 to properly feed the work. There is also a cut-out portion, as at 38, at the rear end of this guide to permit the feeding means 6 of the second sewing mechanism to properly feed the material. The overhanging or top wall 36 of this guide is cut away at the rear end, as at 39, for clearance of the presser foot, while a portion of the vertical wall 40 extends directly up to the needle of the second sewing mechanism 3 to properly control the work. Projecting close to the stitching position of the rear stitching mechanism 2 is a guiding finger 41 attached to and carried by the overhanging wall 3 (see Fig. 8) for guiding the folded edge of the overturned ply to the second stitching position.

The presser foot 5 of sewing mechanism 2 is preferably a compensating foot provided with a vertically-yielding, right-hand portion 42 to act upon the three thicknesses of material 43 (see Fig. 11), while the left-hand portion 44 of the foot operates at a lower level on the single ply 18 of the material. The construction of this presser foot thus provides a guiding means for the folded edges 34 of the seam (see Fig. 11). The front end of the foot portion 44 has a bent-up, laterally-extending portion 45 providing a space underneath for the extra thicknesses of the fold in the material. This portion 45 of the foot covers the space formed by cutting away the overhanging wall 36, at 39, of the guide 33 while leaving space for the feeding of the work freely over and around the guide finger 41 which projects parallel to the foot portion 44 underneath the foot portion 45 and directly up to and in front of the needle of sewing mechanism 2.

To support the U-shaped guiding means so as to properly control the work as it passes from one sewing mechanism to the other, a bracket 46 (see Fig. 8) is provided to which the U-shaped guide 33 is attached. This bracket is provided with elongated slots 48 whereby it may be attached, as at 49 (see Fig. 2) to the cloth plate of sewing mechanism 3.

The overturning or flop-over means has attached thereto members that assist in the overturning and controlling of the work, which members also strengthen and give rigidity to the parts. Attached to the top of the arm of sewing mechanism 3, as at 50, is a flat brace member 51 having its opposite end attached, as at 52, to the projecting face plate 28. Also attached, as at 50, is a curved wire 53 which also forms a brace and work control member, the other end of which is attached, as at 54, to one of the screws 27. Attached, at 55, to the laterally-projecting flange 31 of the member 21 is also a wire work control guide 56 which is shaped approximately as shown in Figs. 1, 2 and 4. The guide so acts upon the work as to remove wrinkles during the flopping-over of the top ply. Also attached to the flange 31, as at 57 and 58 (see Fig. 2), are laterally-projecting members 59 and 60 located at an angle and in the path of travel of the top ply of material. These members act upon the top ply to lay it over flat and have a gentle pressing-down effect while at the same time forcing it to the left of the needle to prevent wrinkles forming in the material at the stitching position. These control members have to be arranged according to the kind and character of work. Flimsy material requires a slightly different control than materials of heavier textures, but these members are readily arranged to suit the kind and character of work and in some instances are not needed at all.

In some cases, to facilitate the handling

of the work by the operator, I provide an auxiliary table of suitable material having a portion extending into the space 61 (see Fig. 2), with the right-hand edge at 62. This table may extend to the left of the needles a distance equal to the width of the work operated upon. While this table is not essential for all kinds of work, it nevertheless is of advantage on work such as overalls.

10 By means of this improved machine and method of forming seams the work heretofore done on separate machines with independent operators, requiring double handling of the work, may be done with one handling 15 of the work by a single operator, whereby the work is done in half the time formerly required.

It is to be understood that by describing in detail herein any particular form, structure, 20 or arrangement, it is not intended to limit the invention beyond the terms of the several claims or the requirements of the prior art.

Having thus explained the nature of my said invention and described a way of constructing and using the same, although without attempting to set forth all of the forms in which it may be made or all of the modes 90 of its use, I claim:

1. In a machine for sewing multiple seams, 25 the combination of means for stitching superposed plies of material with a row of stitches, means for overturning a ply of material and throwing it in a direction opposite to its companion ply thereby forming a triple-ply seam, 30 and means for stitching the triple plies with another row of stitches in parallelism with the first row thereof thereby to form a French-felled seam.

2. In a machine for sewing multiple seams, 40 the combination of means for stitching superposed plies of material with a row of stitches, means for guiding the stitched seam margins of the superposed plies of material in the plane of the bottom ply of material, means 45 for overturning a ply of material and throwing it in a direction opposite to its companion ply thereby forming a triple-ply seam, and means for stitching the triple plies with another row of stitches in parallelism with the 50 first row thereof thereby to form a French-felled seam.

3. In a machine for sewing multiple seams, 55 the combination of means for stitching superposed plies of material with a row of stitches, means for guiding the stitched seam margins of the superposed plies of material in the plane of the bottom ply of material, means for overturning a ply of material and throwing it in a direction opposite to its 60 companion ply thereby forming a triple-ply seam, means for pressing down the overturned ply, and means for stitching the triple plies with another row of stitches in parallelism with the first row thereof thereby to form a French-felled seam.

4. In a machine for sewing multiple seams, 70 the combination of means for stitching superposed plies of material with a row of stitches, means for overturning a ply of material and throwing it in a direction opposite to its companion ply thereby forming a triple-ply seam, means for engaging the overturned ply to prevent the wrinkling thereof as it is fed to its final stitching position, and means for stitching the triple plies with another row 75 of stitches in parallelism with the first row thereof thereby to form a French-felled seam.

5. In a machine for sewing multiple seams, 80 the combination of a pair of sewing mechanisms located one behind the other to sew parallel rows of stitches, one row after the other, means therebetween for guiding the stitched edges of superposed plies of material from one sewing mechanism to the other, means therebetween for overturning a ply of the work over said guiding means, means therebetween for controlling the width of the seam margins, means therebetween for holding down the overturned ply, and means therebetween for preventing the wrinkling 90 of the overturned ply.

6. In a machine for sewing multiple seams, 95 the combination of a pair of sewing mechanisms located one behind the other to sew parallel rows of stitches, one row after the other, means in position to guide the edges of superposed plies of material to the first stitching position, means between the sewing mechanisms for guiding the stitched edges of the superposed plies of material from one sewing mechanism to the other, means co-operating with the second guiding means for controlling the width of the seam, and means between the sewing mechanisms for overturning a ply of the work for the passage of 100 the triple plies thus formed to the second sewing position.

7. In a machine for sewing multiple seams, 105 the combination of a pair of sewing mechanisms located one behind the other to sew parallel rows of stitches, one row after the other, means in position to guide the edges of superposed plies of material to the first stitching position, means between the sewing mechanisms for guiding the stitched edges of the superposed plies of material from one sewing mechanism to the other, means co-operating with the second guiding means for controlling the width of the seam, means between the sewing mechanisms for overturning a ply of the work for the passage of the triple plies thus formed to the second sewing position, and a guide finger carried by the second guiding means for guiding the work to the second sewing position.

8. In a machine for sewing multiple seams, 120 the combination of a pair of sewing mechanisms located one behind the other to sew parallel rows of stitches, one row after the other, means in position to guide the edges of 125

- superposed plies of material to the first stitching position, means between the sewing mechanisms for guiding the stitched edges of the superposed plies of material from one sewing mechanism to the other, means co-operating with the second guiding means for controlling the width of the seam, means between the sewing mechanisms for overturning a ply of the work for the passage of the triple plies thus formed to the second sewing position, and presser foot mechanism carried by the second sewing mechanism for guiding and holding down the work during the stitching of the second row of stitches. 5 70
- 10 9. In a machine for sewing multiple seams, the combination of a pair of sewing mechanisms located one behind the other to sew parallel rows of stitches, one row after the other, means in position to guide the edges 15 75
- 20 of superposed plies of material to the first stitching position, means between the sewing mechanisms for guiding the stitched edges of the superposed plies of material from one sewing mechanism to the other, means co- 25 operating with the second guiding means for controlling the width of the seam, means between the sewing mechanisms for overturning a ply of the work for the passage of the triple plies thus formed to the second sewing 30 80
- 30 10. In a machine for sewing multiple seams, the combination of a pair of sewing mechanisms located one behind the other to 40 85
- 40 sew parallel rows of stitches, one row after the other, a U-shaped guide therebetween for guiding the stitched edges of the superposed plies of material from one sewing mechanism to the other, and means between 45 90
- 45 said sewing mechanisms for overturning a ply of work over said guiding means. 50 95
- 50 11. In a machine for sewing multiple seams, the combination of a pair of sewing mechanisms located one behind the other to 55 100
- 55 sew parallel rows of stitches, one row after the other, a U-shaped guide therebetween for guiding the stitched edges of the superposed plies of material from one sewing mechanism to the other, means between said sewing mechanisms for overturning a ply of work over said guiding means, and means co-operating with said guiding means for controlling the width of the seam. 60 105
- 60 12. In a machine for sewing multiple seams, the combination of a pair of sewing mechanisms located one behind the other to 65 110
- 65 sew parallel rows of stitches, one row after the other, a U-shaped guide therebetween for guiding the stitched edges of the superposed plies of material from one sewing mechanism to the other, means co-operating with the second guiding means for controlling the width of the seam, said means having a scalloped formation. 70 115
- 70 13. In a machine for sewing multiple seams, the combination of a pair of sewing mechanisms located one behind the other to 75 120
- 75 sew parallel rows of stitches, one row after the other, means for guiding the work to the first stitching position, means for guiding the work to the second stitching position, and means between the sewing mechanisms for overturning a ply of the work to form a triple-ply seam and permit the triple plies thus formed to be sewed by the second row of stitches. 80 125
- 80 14. In a machine for sewing multiple seams, the combination of a pair of sewing mechanisms located one behind the other to 85 130
- 85 sew parallel rows of stitches, one row after the other, and means therebetween for overturning a ply of material and throwing it in a direction opposite to its companion ply, said means including means for separating the unstitched portion of the plies and means for gradually raising the ply and overturning the same. 90 135
- 90 15. In a machine for sewing multiple seams, the combination of a pair of sewing mechanisms located one behind the other to 95 140
- 95 sew parallel rows of stitches, one row after the other, and means therebetween for overturning a ply of material and throwing it in a direction opposite to its companion ply, said means including means for separating the unstitched portion of the plies and means for gradually raising the ply and overturning the same and comprising a member having an inclined vertically-located edge. 100 145
- 100 16. In a machine for sewing multiple seams, the combination of a pair of sewing mechanisms located one behind the other to 105 150
- 105 sew parallel rows of stitches, one row after the other, and means therebetween for overturning a ply of material and throwing it in a direction opposite to its companion ply, said means including means for separating the unstitched portion of the plies and means for gradually raising the ply and overturning the same and comprising a member having an inclined vertically-located edge and a plurality of laterally-curved members. 110 155
- 110 17. In a machine for sewing multiple seams, the combination of a pair of sewing mechanisms located one behind the other to 115 160
- 115 sew parallel rows of stitches, one row after the other, and means therebetween for overturning a ply of material and throwing it in a direction opposite to its companion ply, said means including means for separating the unstitched portion of the plies and means for gradually raising the ply and overturning the same and comprising a 120 165
- 120 18. In a machine for sewing multiple seams, the combination of a pair of sewing mechanisms located one behind the other to 125 170
- 125 sew parallel rows of stitches, one row after the other, and means therebetween for overturning a ply of material and throwing it in a direction opposite to its companion ply, said means including means for separating the unstitched portion of the plies and means for gradually raising the ply and overturning the same and comprising a 130 175

member having an inclined vertically-located edge and a plurality of laterally-curved, wire-formed members.

18. The method of stitching articles to form a French-felled seam which consists in stitching two superposed plies of material with a row of stitches, then while such row of stitching is being applied simultaneously and automatically gradually separating the plies at the forward end thereof and overturning that part of one of the plies so stitched to form a triple ply at the seam portions thereof, and then stitching the triple plies with a row of stitches parallel to the first row.

19. The method of stitching articles to form a French-felled seam which consists in first stitching two superposed plies of material with a row of stitches, then guiding the so-stitched seam during the feeding thereof into position to be again stitched and simultaneously with such guiding of the superposed plies automatically overturning one of said plies to form a triple-ply seam, and then stitching the triple plies with a second row of stitches in parallelism with the first row.

20. The method of stitching articles to form a French-felled seam which consists in first stitching two superposed plies of material with a row of stitches, then guiding the so-stitched seam during the feeding thereof into position to be again stitched and simultaneously with such guiding of the superposed plies automatically and gradually overturning one of said plies to form a triple-ply seam, and then stitching the triple plies with a second row of stitches in parallelism with the first row.

40 Signed at Nyack, county of Rockland and State of New York this 29th day of Nov. 1929.

JOHN P. WEIS.
